UNITED STATES PATENT OFFICE.

VICTOR B. NELSON, OF ROCKFORD, ILLINOIS.

STARTING DEVICE FOR INTERNAL-COMBUSTION ENGINES.

Application filed July 11, 1924. Serial No. 725,827.

This invention relates to devices for starting internal combustion engines from a condition of rest and has more particular reference to manually operated devices for this purpose. Devices of this kind are especially adapted for starting small engines, either stationary or portable. My invention, however, is not limited to the use of manual force as the impelling power but might be employed with other forms of motor power, as will be apparent hereinafter.

The purpose of my invention is to provide a simple and improved starting device employing a spirally wound element which when unwound by a constant pull and constant motion will impart uniformly accelerating rotary motion to the crank-shaft of the engine. If the impelling motion is varied or accelerates, the rotary motion imparted to the crank-shaft will be proportionally accelerated.

My invention is applied in a practical manner as disclosed herein, to the flywheel of a small portable engine of the kind used for propelling canoes, rowboats and the like. In this embodiment I have provided a conical body on a flywheel having a spiral groove in its periphery, in which groove a rope or cord is adapted to be wound after having been detachably fastened to the smaller end of the conical body so that when the free end of the rope is pulled steadily in a constant lineal motion, uniformly accelerating rotary motion will be imparted to the flywheel, or if the impelling motion is accelerated the flywheel motion will be proportionally accelerated. This is especially advantageous because a greater number of complete revolutions will be imparted for a given length of groove than with helical grooves or such as are provided on a cylindrical body and, furthermore, because the accelerating motion brings the speed closer to the normal engine speed, constantly facilitating initial functioning of the engine.

Referring to the accompanying drawing, Figure 1, is a side elevation showing briefly the outline of an internal combustion engine equipped with a starting device embodying my invention; and

Fig. 2, is a top view of said device and the flywheel as it is shown in Fig. 1.

In the present embodiment of my invention the starting device is applied directly to the flywheel of an internal combustion

engine of the portable type adapted for propelling small boats. As shown in Fig. 1 this is an opposed double cylinder engine designated generally by 3, the crank-shaft 4 of which is on a vertical axis and the flywheel 5 is fixed to the upper end of the crank-shaft.

My improved starting device consists in this embodiment of a frusto-conical body or plate designated generally by 6 fixed by suitable means such as screws 7 to the upper side of the flywheel coaxial therewith. In the periphery of this body is formed a spiral groove designated by 8 which winds about and rises on said body so that the smallest convolution terminates at the upper base thereof, at which point the body is recessed to provide a hook 9. A suitable rope or cord, provided at one end with a knot which may be engaged in the recess of the hook, or a loop which may be engaged over the hook, will be wound in the groove in a clockwise direction, viewing Fig. 2 so as to emanate tangentially from the lowermost convolution. When this end of the rope is pulled evenly in a constant motion the flywheel will be turned in a uniformly accelerating motion. If the pull on the rope is varied to increase the speed, the motion imparted to the flywheel will be correspondingly and proportionally increased at the accelerating ratio. The end of the rope fastened to the hook 9 will automatically release therefrom when the innermost end of the groove is reached. This provides a very effective starting device for reasons explained above.

In the present application I have illustrated but a single working embodiment of my invention, the essential feature of which is the use of a starting element connected to an engine crank-shaft and winding about an axis and rising in a cone so as to impart accelerating motion to the crank-shaft when unwound in the manner described. It should be understood therefore that my invention might be embodied in different forms without departing from its spirit and scope as expressed in the appended claims, in which—

I claim:

1. A device for starting internal combustion engines comprising, in combination, the crank-shaft, a frusto-conical body connected to said crank shaft and having a spiral

- groove in its periphery, the convolutions of the groove decreasing in diameter toward the smaller base of said body, and means for releasably attaching a rope or cord to the body 5 at the inner end of the groove, whereby said rope after having been wound in said groove may be pulled for imparting accelerating rotary motion to the crank shaft.
2. A starting device for internal combustion engines comprising, in combination, an engine crankshaft, and a body connected to rotate with said crankshaft, said body having a peripheral groove winding in convolutions thereabout and having at one end means for 10 detachably connecting a rope or cord thereto, whereby a rope attached to the body and wound in said groove may be pulled at its free end for imparting rotary motion to the body, the convolutions at the end of the 15 groove at which the rope is attached to the body being of less radius than that at the opposite end of the groove at which the motion is initiated, whereby greater leverage is obtained in imparting the initial rotary motion 20

and said motion will be accelerated with constant lineal pull of the rope. 25

3. In a device of the character described, the combination of a shaft to be spun, a rope for spinning the shaft, and a device for providing a detachable driving connection between said rope and said shaft, having said rope wound thereon from a point on a small radius through a number of turns to a point on a comparatively large radius, to afford greater leverage in starting from rest and decreasing leverage after starting. 30

4. In a device of the character described, the combination of a shaft to be spun, a rope for spinning the shaft and a pulley providing a detachable driving connection between 35 said rope and said shaft, said pulley having a periphery for winding said rope thereon which starts with a point on a small radius and extends to a point on a comparatively large radius to afford greater leverage in 40 starting from rest as the rope is unwound and decreasing leverage after starting. 45
